TO THE TWITCHELL PROCESS COMPANY, OF CINCINNATI, OHIO, A CORPORATION
OF OHIO

PROCESS OF REMOVING OIL FROM MINERAL-OIL-SULPHONIC BODIES

No Drawing.

Application filed June 29, 1926. Serial No. 119,483.

Our invention relates to a process of separating oil and sulphonated components thereof.

The oils embraced within the scope of this invention are those hydrocarbon oils characterized by the presence of certain components susceptible to modification by the action of sulphuric acid and certain components not susceptible. Oils such as petroleum, shale oil and coal tar oil, gilsonitic distillates and many other fractions or distillates of hydrocarbon deposits usually exemplify this characteristic.

Since petroleum is commercially available at present in large quantities, the following disclosure is made in relation thereto.

When petroleum or fractions thereof, such as lubricating stock, are treated with sulphuric acid, certain components of the oil are modified. The theory chemically accepted at present explains this modification as sulphonation, i. e. the sulphuric acid reacts with components of the mineral oil (the unsaturated components, supposedly) to form mineral oil sulphonic acid. The yield of sulphonated acid is higher when the oil is treated with fuming sulphuric acid, so this disclosure is also made in relation to this fuming sulphuric acid treatment.

It is further theory that these mineral oil sulphonated acids can be reacted with metallic substance or compounds such as sodium hydroxide or sodium carbonate, for instance, to produce salts of mineral oil sulphonated acid. Research to date seems to indicate that these assumptions are correct, but in the ensuing description of the invention and the claims, it is to be understood that the procedure and products thereof as described is the real substance of the invention and that the chemical explanation is merely offered for the benefit of the skilled in the art.

This above described sulphonating treatment is practiced on a large commercial scale in the refining of medicinal white oil. In this refining operation the sulphonated components are the by-products and are commercially available as such at present. These sulphonated components are usually available in the form of alkaline salts since

the sulphonated components in the acid state have a highly corrosive action on iron or steel pipes or containers. The advantage of treating, shipping or handling these sulphonated components in a neutral state is a continuing one.

The process of refining the white oil and extracting the sulphonates is described and claimed in U. S. Patent No. 1,087,888 to Grigori Petroff, issued February 17, 1914; U. S. Patent No. 1,233,700 to Grigori Petroff, issued July 17, 1917; U. S. Patent No. 1,196,274 to Grigori Petroff, issued August 26, 1916, and a specific process in U. S. Patent No. 1,286,179 to Robert E. Humphries, issued November 26, 1918.

The sulphonated bodies commercially available as a result of the practice of the above specified processes are known as commercially pure. These processes do not completely separate all of the oil from the sulphonated components. In fact, the oil and sulphonated components are so intimately mixed, so closely associated and/or possessed of such physical affinity for each other that complete or even approximately complete removal of all the oil has not heretofore been practical.

Therefore one object of our invention is to provide a process of separating oil and sulphonated components thereof.

Another object of our invention is to provide a process of removing oil from the mineral oil-sulphonates available as a result of the practice of the Petroff, Humphries and other known commercial processes.

In commercial practice a mineral oil fraction such as a lubricating stock is treated with fuming sulphuric acid. Two layers are formed. The upper layer is known as the A layer and the lower layer as the B layer. The A layer containing sulphonated acids known as mahogany acids is removed and treated with dilute aqueous alcohol and sodium carbonate. Again two layers are formed. The upper layer is known as the oil layer and the lower layer known as the alkaline alcoholic sublye. The lower layer contains sodium sulphonates known in the art as mahogany soap. The layers are parted and the aqueous alcohol is distilled from the lower layer leaving the ma-

hogany soap with approximately 20-25% oil closely associated therewith.

We remove the oil from the sulphonated components thereof by distillation with 5 super-heated steam. The oil is carried off by the steam in a vapor phase leaving the sulphonated bodies behind. Any suitable still can be used for this treatment, such as a still used for distillation of fatty acids. A still 10 of the vacuum type is recommended, though atmospheric stills can be used.

In treating a mahogany soap such as is produced as above described, the soap is first dehydrated by heating it to a temperature 15 between 100° and 110° C.

The mahogany soap can be dehydrated either in the still, or in any other suitable apparatus. We prefer not to use the still for this purpose as there is considerable foaming 20 during dehydration and therefore there is danger of soap coming over into condensers or catchalls. Also this foaming can be watched and controlled more easily in an open tank than in a still, then, too, dehydra- 25 tion is accomplished faster in an open tank, for the sides and top of the still would act as a condenser for the water vapors that come from soap, giving reflux action. After 30 which denotes a satisfactory degree of de- hydration.

The mahogany soap is then introduced into the still and heated to an oil distilling range of temperature usually between 185° and 230° 35 C. Super-heated steam of slightly higher temperature, 25° C. for instance, is then introduced through a distributor at the bottom of the still. The steam so introduced serves as an agitator for the soap. The oil is car- 40 ried off by the steam in vapor phase and can be recovered as a by-product by condensation.

The percentage and amount of oil removed depends upon the length of the treatment and the degree of heat, the amount increasing with 45 each and both.

For instance, if a mahogany soap containing about 25% oil is dehydrated, then heated to about 200° C. and then agitated with super-heated steam at 225° C. for a period of from 50 6 to 8 hours, all but about 5% of the oil will be removed. The resulting product though not chemically pure provides a far more powerful reagent than the original mahogany soap when both are reconstituted as acids for 55 fat splitting purposes, for instance, in the soap industry.

Thus we provide a process of removing oil from the sulphonated components of the oil in order to render more potent sulphonated re- 60 agents commercially available.

Having described our invention, we claim:

1. The process of purifying mahogany sul- 65 phonates which comprises dehydrating the sulphonates and agitating the sulphonates with superheated steam to remove in vapor

phase the unsulphonated oils and leave as a remainder intact the mahogany sulphonates.

2. The process of purifying mahogany sul- 70 phonates which comprises dehydrating the sulphonates by heating them to a temperature of between 100-110° C. then heating the sulphonates to an oil distilling temperature of between 185-230° C. and then agitating the sulphonates with steam super-heated at ap- 75 proximately 25° C. above the oil distilling temperature to remove in vapor phase the un- sulphonated oils and leave as a remainder intact the mahogany sulphonates.

In witness whereof, we hereunto subscribe our names.

CHARLES FISCHER, JR.
W. T. REDDISH.
